L. MOREL

SPARK PLUG

Filed Aug. 17, 1920

UNITED STATES PATENT OFFICE.

LOUIS MOREL, OF BOULOGNE-SUR-SEINE, FRANCE, ASSIGNOR TO ANTOINE LUCIEN SCHMITZ, OF BOULOGNE-SUR-SEINE, FRANCE.

SPARK PLUG.

Application filed August 17, 1920. Serial No. 404,235.

(GRANTED UNDER THE PROVISIONS OF THE ACT OF MARCH 3, 1921, 41 STAT. L., 1313.)

To all whom it may concern:

Be it known that I, LOUIS MOREL, a citizen of the Republic of France, residing at 43 Rue d'Aguesseau, Boulogne-sur-Seine, Seine, in the Republic of France, have invented certain new and useful Improvements in Spark Plugs (for which I have filed applications in France, application filed July 5, 1919, granted April 30, 1920, No. 505,171, 10 and application filed September 19, 1919, granted February 8, 1921, No. 22,595; in Germany, application filed May 22, 1920, granted February 22, 1922, No. 352,203; in Belgium, application filed July 2, 1920, 15 granted August 14, 1920, No. 288,445; in Switzerland, application filed July 2, 1920, granted November 16, 1921, No. 91,681; in Spain, application filed July 3, 1920, granted October 9, 1920, No. 74,437; in Italy, application filed July 3, 1920, granted September 18, 1922, No. 54,624; in Great Britain, application filed July 5, 1920, accepted May 26, 1921, No. 146,824; in Austria, application filed July 9, 1920, granted April 11, 20 25 1922, No. 89,316; in Canada, application filed July 21, 1920, allowed December 17, 1921, No. 220,126), of which the following is a specification.

In my French Patent No. 495,138 of June 30 10, 1918, is described an ignition spark plug one of the particular features of which consists in the fact that the electrode is made in sections within the spark plug in such manner as to provide for the breaking of 35 the current within the body of the plug.

The spark plug which is the object of this invention is based upon the same principle but contains the following improvements:

A. The spark break is not obtained by 40 cutting the electrode, but by adding at a suitable point a flanged ring surrounding, but with a certain amount of play, a conducting portion provided upon the electrode. By this disposition the spark plug may be 45 reduced in length if desired and it is no longer necessary to divide the electrode into two parts, whereby the assembling of the spark plug is simplified and it will have a stronger construction.

B. The insulation in this spark plug is carried out in certain cases by means of a sheathing in mica or like material. In spite

of the care and the precautions which are taken when mounting a mica sheathing upon a central electrode, this sheathing is liable 55 to lose a part of its insulating properties under the action of the great heat prevailing in the case of high power motors. Attempts have been made to obviate this inconvenience by the use of an air draught, but this method 60 can only be of benefit to those portions of the sheathing which are situated farthest from the explosion chamber, i. e., which are less exposed to injury, and this method is therefore insufficient. 65

This invention provides a remedy for this inconvenience either by suppressing the use of mica as an insulating material and replacing the same by porcelain, or by removing the mica a considerable distance from 70 the explosion chamber, whereby the mica shall be no longer liable to lose its insulating properties.

The following description together with the accompanying drawings which are given 75 by way of example, set forth the nature and the advantages of this invention.

Figs. 1, 2 and 3 show in vertical and axial section spark plugs representing three embodiments of this invention. 80

As indicated in the drawings, the electrode *a* is imbedded in a sheath of insulating material *b* for instance in mica, which is constituted in the form of a cone *c* with a cylindrical extension *d*; between these two 85 portions *c* *d* is disposed a conducting washer *e* constructed together with the electrode *a*. The male conical portion *b* engages a portion constituting the female cone of a socket *f* which is screwed upon the cylinder by 90 means of its threaded portion *g*. The said socket *f* supports a ring *h* of insulating material for instance fibre; upon the said ring is disposed a flanged ring *i* of conducting material, for instance copper. Upon the 95 flanged ring *i* and around the cylindrical portion *d* of an insulating sheathing of the rod *a* is disposed a ring of insulating material, for instance in fibre *j* having disposed thereon a washer *k* through which passes the 100 upper part of the electrode *a* which has a threaded portion *a'*. A nut *l* on the threaded portion bears upon a washer *m* and maintains the electrode *a* in its sheathing *b*; at

the upper end of the threaded rod a^1 is screwed a nut forming a cap n to which can be connected a terminal o ; a second terminal p can be connected to the ring i .

5 The various members constituting the spark plug are so assembled that between the ring i and the conducting washer e which is secured to the electrode a , there will exist an annular interval or space r in which the 10 break of the current will be produced.

As will be observed, this spark plug may contain two current terminals o p , this arrangement allowing the spark plug to operate as an ordinary plug; the current which 15 arrives at o passes through the electrode a and the spark is produced between the head q and the threaded end g ; this circuit will be traversed by the current at the moment of starting, inasmuch as the tension is now insufficient for crossing a spark gap. When 20 the motor is started the current arrives at p , then passes into the ring i and after the break of the current, it passes through the washer e to the lower portion of the electrode 25 a and produces a spark between the head q and the threaded end g .

The mounting of the current terminal members upon the nut n and the ring i can be carried out in any suitable manner, for 30 instance by means of a spring clamp.

The spark plug shown in Fig. 2 comprises the socket of brass or steel screwed into the motor cylinder by means of its screwthread a^{10} ; the insulating member b^0 preferably of porcelain and of special form and the central electrode c^0 terminated at its lower part by a portion c^{10} of pure nickel provided with a shoulder c^{20} and threaded at its upper part c^{30} . As will be observed, the porcelain member 35 b^0 contains a lower portion b^{20} which is relatively thin, an exterior rounded shoulder b^{30} , an upper shoulder b^{40} having connected thereto a truncated cone shaped portion b^{50} . The said porcelain member b^0 40 bears upon the socket a^0 through the medium of its shoulder b^{30} with the interposition of an asbestos joint d^{10} . The central electrode c^0 is held clamped by the nut e^0 and its shoulder c^{20} bears upon the corresponding 45 portion b^{10} of the porcelain member through the intermediary of an asbestos joint d^{20} . The nut e^0 is pressed against the upper part 50 of the porcelain member b^0 , with interposition of a copper washer f^0 and a locking washer f^{10} .

The porcelain member b^0 is pressed upon by the grooved nut g^0 which is screwed into a corresponding threaded portion a^{20} of the said socket and which presses upon 55 the porcelain member through the medium of an asbestos joint d^{30} which is thus held between the shoulder b^{40} , the truncated cone shaped portion b^{50} and the nut g^0 .

A second porcelain member h^0 of cylindrical form is disposed below the nut g^0 , and

between these two members is disposed the flanged ring k^0 provided with a movable collar l^0 containing a lateral screw threaded projection m^0 . A milled terminal nut n^0 is screwed upon the said projection. 70

The spark plug is closed at its upper part by another porcelain member o^0 having bearing thereon the assembling nut p^0 with the interposition of a fibre washer q^0 and a copper washer q^{10} ; above the said nut 75 is disposed the current terminal cap r^0 .

As will be readily understood, the ignition spark occurs between the end c^{10} of the central electrode and the perforated disk a^{20} secured to the socket. When the spark 80 plug operates without a current break, the current arrives by the terminal cap r^0 and passes through the electrode c^0 in the usual manner. When the spark plug operates with spark break, the current arrives in the 85 projection m^0 , passes through the collar l^0 , the ring k^0 , then crosses the spark gap s^0 and proceeds through the electrode rod c^0 as before.

The principal advantage of this method 90 of mounting resides in the safety which is thus obtained. In fact, the spark break only possesses a real advantage provided it is properly adjusted, and the present disposition will always operate under good conditions by reason of the arrangement of the flanged ring k^0 even should the height of the same be somewhat variable, this not being the case with a device having the spark gap at the end of the rod and with a direct 95 clamping together by nut and joints.

The spark plug shown in Fig. 3 also comprises a socket A threaded at A^1 , internally threaded at A^2 and provided at the lower part with a perforated disk A^3 , containing also a central electrode C having a shoulder C^2 and a threaded portion C^3 . But in this case, the porcelain member is simply of annular form, and rests at its lower end B^2 upon the socket A through the medium of an asbestos washer D^1 . 100

The electrode C is surrounded by a mica cylinder U having two truncated cone shaped portions U^1 and U^2 and resting upon the shoulder C^2 through the medium of an asbestos joint D^2 . The porcelain member B is held pressed through the intermediary of an asbestos washer D^3 by a grooved nut G screwing into the threaded portion A^2 of the socket, and having the inner portion thereof 110 turned in conical shape to fit upon the conical portion U^2 of the mica cylinder, the latter being pressed by the nut E through the medium of the copper washer F . 115

The device terminates at the upper part 120 as in the preceding case by the porcelain member H resting upon the washer D^4 , the flanged ring K which leaves a gap at S for the sparking, the collar L and the upper 125 and lateral current terminals. As will be 130

observed, this arrangement separates the mica from the explosion chamber and it is thus out of danger of deterioration.

The above mentioned spark plugs operate in a perfect manner and never become clogged up, even upon motors having considerable leaks.

It is understood that this invention is not limited to the hereinbefore described embodiments nor to the mounting and the nature of the various members, and it is particularly to be observed that the insulating portions may be constructed of fibre, mica, porcelain or the like.

Having thus described the nature of my said invention and the best means I know of carrying the same into practical effect I claim:—

1. A dismountable spark plug adapted to operate with or without disruptive discharge, comprising a central continuous electrode extending throughout the whole length of the spark plug, an insulating member surrounding the lower part of the central electrode, a socket base, means for pressing said insulating member in a gas-tight manner upon the bottom of said socket base while providing for a dismountable disposition, means for pressing the lower end of said electrode within its insulation in a gas-tight manner, while providing for dismountable disposition, a metal ring surrounding a portion of the central electrode which is not covered by said insulating member, means for maintaining said metal ring distanced from the part of the central electrode which is not surrounded by the insulation, the space between the ring and the part of the central electrode not covered by insulation constituting the disruptive discharge gap, means for bringing current to the metal ring for operating the spark plug upon disruptive discharge, and means for bringing current to the end of the central electrode for operating the spark plug without disruptive discharge.

2. A dismountable spark plug adapted to operate with or without disruptive discharge, comprising a continuous central electrode extending throughout the whole length of the spark plug, an insulating member surrounding the lower part of the central electrode, a socket base, a ring

screwing into the screw-threaded end of said socket base and pressing the said insulating member in a gas-tight manner upon the bottom of said socket base, a nut screwing upon said electrode rod and bearing upon the insulating member surrounding said rod in order to connect these two elements together in a gas-tight manner, a metal ring surrounding a portion of the central electrode which is not covered by said insulating member, means for maintaining said metal ring distanced from the part of the central electrode which is not surrounded by the insulation, this space between the ring and the uncovered part of the central electrode constituting the disruptive discharge gap, means for bringing current to the metal ring for operating the spark plug upon disruptive discharge, and means for bringing current to the end of the central electrode for operating the spark plug without disruptive discharge.

3. A dismountable spark plug adapted to operate with or without disruptive discharge, comprising a continuous central electrode of continuous disposition and extending throughout the whole length of the spark plug, an insulating member surrounding the lower part of the central electrode, a socket base, a ring screwing into the screw-threaded end of said socket base in order to maintain said insulating member within said socket base in a gas-tight manner, an insulating sleeve disposed above the said ring screwing into the socket base, a metal ring disposed upon said insulating sleeve, said ring surrounding the upper end of the electrode, an insulating member mounted upon said metal ring and loosely traversed by the end of said electrode rod, a nut screwing upon the screw-threaded end of said electrode rod whereby said metal ring shall be tightened and held in place between its two insulating members, the space between the insulating ring and the end of said electrode rod not covered by insulation constituting the space wherein the disruptive spark is produced, a current terminal in contact with said metal ring and a second current terminal provided at the end of the central electrode rod.

In testimony whereof I affix my signature.
LOUIS MOREL.
